RING WITH TWO BIRTHSTONES WITH NAME OF
DONEE AND DONOR ADJACENT THE STONES

John Michael Tranfield, 1 Eldon Road,
Wallasey, England

Filed Dec. 27, 1963, Ser. No. 77,943

Term of patent 14 years

(Cl. D45—10)

FIG 2

FIG. 1 is a perspective view of a ring with two birthstones with name of donee and donor adjacent the stones embodying my new design; and

FIG. 2 is a perspective view of the side opposite that shown in FIG. 1.

The dominant features of the design reside in the full line portions on the drawing.

An important feature of the design is in the name adjacent each stone.

I claim:

The ornamental design for a ring with two birthstones with name of donee and donor adjacent the stones, as shown and described.
